P. N. HOFFMAN,
FEATHER PINE CHRISTMAS TREE AND METHOD OF MAKING SAME,
APPLICATION FILED OCT. 15, 1917.

1,253,035.

Patented Jan. 8, 1918.

Paul N. Hoffman, Inventor
By His Attorney
Maurice Block

UNITED STATES PATENT OFFICE.

PAUL N. HOFFMAN, OF NEW YORK, N. Y.

FEATHER-PINE CHRISTMAS TREE AND METHOD OF MAKING SAME.

1,253,035.

Specification of Letters Patent. Patented Jan. 8, 1918.

Application filed October 15, 1917. Serial No. 196,645.

To all whom it may concern:

Be it known that I, PAUL N. HOFFMAN, a subject of the Emperor of Germany, residing at New York city, county and State of 5 New York, have invented certain new and useful Improvements in Feather-Pine Christmas Trees and Methods of Making Same, of which the following is a full, clear, and exact description:

10 This invention relates to a process of forming the branches, twigs, etc., which go to make up an artificial tree, particularly a Christmas tree. My invention will produce what is known as a feather-pine Christmas 15 tree, it being an improvement over the method heretofore employed in that such a tree can, by my process, be produced much cheaper and more quickly than by the method now in vogue.

20 As far as I am aware, artificial Christmas trees are produced by wiring what is known as preserved feather-pine stems to a wire, a combination of these wires and attached stems being assembled into the form of a 25 tree by employing branches into which the wires, to which the stems are attached are inserted. The wiring of these stems to the supporting wire is a slow and tedious process; furthermore it is not a substantial structure 30 as the stems fall over during shipment and handling.

While I employ a supporting wire and the preserved stems which are attached thereto, I employ an entirely different means and 35 method of securing the stems to the supporting wire, producing a much more substantial structure.

I will now proceed to describe my invention in detail, the novel features of which, I 40 will point out in the appended claims, reference being had to the accompanying drawing, forming part hereof, wherein:—

Figure 1 is a fragmentary view illustrating my improved method of assembling the 45 stems preparatory to application to the supporting wire;

Fig. 2 is a similar view illustrating a portion of a finished strip;

Fig. 3 is a plan view of a form of winding 50 mechanism which forms a part of the operation of forming the strip;

Fig. 4 is a side view thereof; and

Fig. 5 is an enlarged sectional view, the section being taken on a line 5—5 in Fig. 3.

55 To carry my invention into practice, I employ a tape 6 (Fig. 1) of any desired length,

and to the tape I secure, at certain intervals, twigs 7 of preserved feather-pine, or the like. The twigs 7 are secured to the tape by being stitched as indicated at 8; hence they are 60 securely fastened thereto and cannot come off.

After the tape has been prepared by securing thereto the desired number of twigs, it is wound upon a supporting element 9, consisting preferably of a wire that can be 65 bent or flexed. To facilitate the operation, I preferably stretch the wire from a swivel 10 to a rotatable ring 11 (or chuck, if desirable), carried by a disk 12 on a shaft 12^a rotated by a belt 13 and pulley 14, the shaft 70 being supported by a bearing 15. One end of the prepared tape is fastened to the wire 9 as at 16, Fig. 1. After the tape has been secured to the wire 9, the machine will be started and the wire 9 will revolve, thereby 75 winding the tape thereupon, as indicated in Fig. 2. While the tape is being wound upon the wire, it is passed over a roller 17 running in glue, paste or cement 18 (see Fig. 5) in a pot 19. The pot 19 is slidably mounted 80 upon a square rod or support 20, and as the tape winds up upon the wire 9, the pot will be correspondingly moved along the rod 20. The tape, as well as glue-pot, may be fed by hand or otherwise. The cement or glue, 85 which is applied to the tape, will cause the superimposed convolutions to adhere together and will also aid the stitching to secure the twigs to the tape. In short, the cement or glue will act to produce a substantially integral mass after it has dried. Any device that is arranged to revolve the supporting wire will answer for my purpose, 90 the device herein described being illustrative only.

The finished article will consist of a long strip of wire covered, as described, by the grouped twigs of feathered-pine. As the twigs are preferably evenly spaced upon the tape, they will be evenly grouped around the 100 wire 9, and not in bunches, as frequently occurs with wiring methods.

After the tape has been completely wound upon the wire 9, it may be secured at its end to the wire by wiring or otherwise.

105 It will of course be understood that my invention is adaptable not only for Christmas tree branches, but also for the manufacture of artificial wreathes and kindred articles.

What I claim as my invention is:

110 1. An article of manufacture consisting of a strip of flexible material having stitched

thereto in spaced relationship twigs of feathered pine or the like.

2. The method of forming branches for artificial Christmas-trees, consisting in permanently securing in spaced relationship twigs of feathered-pine or the like to a flexible tape, and winding said tape around a supporting wire after the twigs have been secured to the tape.
- 5 3. The method of forming branches for artificial Christmas-trees, consisting in stitching twigs of feathered-pine or the like to a flexible tape, applying cement or glue to said tape, and finally winding the cement coated tape around a supporting wire.
- 10 4. The method of forming branches of artificial Christmas-trees, consisting in first independently and permanently securing to a tape a plurality of twigs of feathered-pine

or the like in spaced relationship, then winding the tape having the previously spaced twigs to a supporting wire, and securing the ends of the tape to the wire.

5. As a new article of manufacture, an artificial Christmas-tree-branch, consisting of a flexible stem having spirally wound thereon a tape provided with spaced apart twigs or the like, extending therefrom, said twigs being permanently secured to the tape independently of the stem, and means to maintain the tape in wound position on the stem.

Signed at New York city, N. Y., this 13 day of October, 1917.

PAUL N. HOFFMAN.
